UNITED STATES PATENT OFFICE

2,499,754

COMPASS TOOL

Clarence P. Huls, Portland, Oreg.

Application August 16, 1946, Serial No. 691,023

2 Claims. (Cl. 33—30)

1

The present invention relates to compasses and is more particularly concerned with a scribe marker or for shop or field work.

The primary object of the invention is to provide a device of the character referred to which can be readily adjusted to work of irregular shape and various sizes.

Another object of the invention is to provide a device of the character referred to of simple and inexpensive construction.

With the foregoing and other objects and advantages in view the invention consists of the novel construction and arrangement of parts hereinafter described and claimed.

In the accompanying drawings illustrating the preferred embodiment of the invention,

Figure 1 is a front elevation of the device

Figure 2 is a section thereof on line 2—2 of Figure 1

Figure 3 is a fragmentary top plan view

Figure 4 is a fragmentary view of the lower portion of one of the tripod legs—

Like numerals, as used in the description and drawings, designate the same structural parts.

The scribe is constructed in tripod form so as to provide stability at the base. It comprises three legs 10, 11 and 12, with eyes at the upper ends to engage a ring 13 which serves to tie them together. The pivotal and sliding connections of the legs with the ring is sufficiently loose to permit leg 10 to gravitationally maintain a perpendicular position even when ring 13 assumes an inclination to the horizontal as legs 11 and 12 are rested upon portions of the surface to be scribed having different elevations with respect to the horizontal.

The leg 10 is somewhat shorter than the others and all three are tubular at the lower ends. Threaded in these extremities are pointed elements 14. When it becomes desirable to lengthen the tripod legs, extension members provided with points, may be threaded on the pointed elements 14.

The leg 10 is designed to serve as a compass leg. To this end it is provided with a rotatable scribe 15, either a tool or pencil. The scribe is held adjustably in a clasp 16 having an ear 17 which is secured to an ear 18 on a vertically adjustable sleeve 19 mounted on the leg 10. Ears 17 and 18 are joined by means of a bolt and wing-nut 20 to permit adjustment of the scribe radially, thus allowing the lay-out of openings or profiles for pipes and other cylindrical objects designed to pass through or intersect other ob-

2

jects or surfaces, such as floors, desks, bulkheads, walls, pipes, etc.

The scribe being adjustable vertically and free to rotate on the leg 10 it is possible to mark or scribe materials of irregular form, and the tripodal arrangement of the whole unit allows the tool to be set and provides stability thereof while in use.

As different embodiments may be made of this inventive concept and modifications may be made in the embodiment hereinbefore shown and described, it will be understood that the matter herein is to be interpreted as illustrative merely, and not in a limiting sense.

What I claim is:

1. A scribe comprising a substantially horizontal ring, a pair of normally downwardly divergent legs, means pivotally and slidably connecting the upper ends of said divergent legs on said ring to slide around said ring toward and away from each other and to swing toward and away from each other, and a normally perpendicular scribe leg having a centering point on its lower end for engaging a surface to be scribed, means pivotally and slidably connecting the upper end of said scribe leg to said ring to slide around said ring toward and away from said divergent legs and to swing into positions angulated with respect to the perpendicular, eccentric scribe means, and means mounting said eccentric scribe means on said scribe leg for vertical adjustment thereon and for rotation of said scribe means on the axis of said perpendicular leg for scribing a curved line on the surface to be scribed.

2. A scribe comprising a substantially horizontal ring, a pair of normally downwardly divergent legs, means pivotally and slidably connecting the upper ends of said divergent legs on said ring to slide around said ring toward and away from each other and to swing toward and away from each other, and a normally perpendicular scribe leg having a centering point on its lower end for engaging a surface to be scribed, means pivotally and slidably connecting the upper end of said scribe leg to said ring to slide around said ring toward and away from said divergent legs and to swing into positions angulated with respect to the perpendicular, eccentric scribe means, and means mounting said eccentric scribe means on said scribe leg for vertical adjustment thereon and for rotation of said scribe means on the axis of said perpendicular leg for scribing a curved line on the surface to be scribed.

3. A scribe comprising a substantially horizontal ring, a pair of normally downwardly divergent legs, means pivotally and slidably connecting the upper ends of said divergent legs on said ring to slide around said ring toward and away from each other and to swing toward and away from each other, and a normally perpendicular scribe leg having a centering point on its lower end for engaging a surface to be scribed, means pivotally and slidably connecting the upper end of said scribe leg to said ring to slide around said ring toward and away from said divergent legs and to swing into positions angulated with respect to the perpendicular, eccentric scribe means, and means mounting said eccentric scribe means on said scribe leg for vertical adjustment thereon and for rotation of said scribe means on the axis of said perpendicular leg for scribing a curved line on the surface to be scribed, the pivotal and sliding connections of the legs with said ring being sufficiently loose to permit

3

said scribe leg to gravitationally maintain a perpendicular position even when said ring assumes an inclination to the horizontal as said divergent legs are rested upon portions of the surface to be scribed having different elevations with respect to the horizontal.

CLARENCE P. HULS.
